**APPARATUS FOR FORMING OPENINGS IN
BLANKS OR PAPER WEB FROM WHICH EN-
VELOPES ARE FORMED**

Hermann Subklew, Neuwied, Rhineland, Germany, assignor to Berkley Machine Company, Kansas City, Mo., a corporation of Missouri

Filed Jan. 24, 1958, Ser. No. 711,041

Claims priority, application Germany Jan. 26, 1957
8 Claims. (Cl. 51—78)

This invention relates to an apparatus for forming openings in the blanks or paper web from which envelopes are formed, and particularly on high speed rotary envelope making machines, the openings being to provide windows which may or may not be subsequently covered with a transparent patch and through which the address portion of a letter placed inside a finished envelope may be seen to supply the mailing address.

Such machines operate at high speed and the blanks or webs from which the envelopes are formed are kept in constant continuous movement, consequently it has been difficult to form the window openings with the blanks or web in motion.

It has been the practice to die cut the envelope blanks and openings therein by pressing a die through a stack of sheets and then feeding the blanks with the openings therein from a stack. This requires separate equipment to provide the blanks and the necessity of transporting the blanks and inserting them in a stack in the envelope making machine. Considerable power is also required to operate the die press.

Another method is die cutting of the windows directly in the envelope making machine, but this requires momentarily stopping the blanks or web while cuts are being made through the material thereof and restricts the production of an otherwise continuous rotary envelope making machine. For this reason, rotary cutting cylinders have been devised for cutting through the blanks or paper web with the blanks or web in motion. This has usually been accomplished by providing the cutting cylinders with one or several knives, acting against a hardened steel roller which serves as a matrice. The knife, cylinder and matrice roller are arranged in a slantwise direction or spiral blades are used to produce as nearly as possible a shear cut progressive with movement of the blank or web. The latter method also has numerous disadvantages. When the knife cylinder acts on the matrice roller of hardened steel, there is a considerable springiness in the knife blades, which results in a more squashing action rather than a clean cut through the material. There is also considerable wear on the knife edges because of their impact on the hard steel matrice roller. Consequently, these disadvantages result in reduced efficiency of the machine. Also, at higher working speeds greater pressure is required between the knife cylinder and the counter-roller which increases the wear on the parts and otherwise interferes with satisfactory cuts being produced.

It is, therefore, the principal object of the present invention to provide a novel apparatus for providing the window openings directly in a continuous rotary type envelope making machine, which overcomes the difficulties of the present methods and permits operation of the envelope making machine at the higher speeds.

Other objects of the invention are to provide an apparatus involving the grinding out of portions of the material of the blanks or web to form the openings neatly and rapidly; to provide a grinding operation wherein both the envelope material and grinding element rotate in contact only where the marginal edge of the window is to be formed; and to provide a method and apparatus wherein the envelope material is presented to the grinding element

2

in a manner to permit passing of the material at substantially high speeds.

In accomplishing these and other objects of the invention, we have provided an improved apparatus illustrated in the accompanying drawings, wherein:

FIG. 1 is a longitudinal section through an apparatus constructed in accordance with the present invention, the section being taken on the line 1—1 of FIG. 3.

FIG. 2 is a fragmentary perspective sectional view of the segment which provides the support for backing the blanks or web for effecting grinding contact of the grinding element with the blanks or web, as the case may be.

FIG. 3 is a plan view of the apparatus, of slightly smaller scale than FIG. 1 and with upper feed roller and pressure wheels removed to better illustrate the construction of the revolvable cylinder and the passes for the paper web or blanks, parts being shown in section for better illustration.

Referring more in detail to the drawings:

20 1 designates an apparatus for forming openings such as windows in envelope blanks and in web material from which the envelopes are formed in a rotary type envelope making machine. The apparatus 1 is interposed between upper and lower feed or guide rollers "B" and "D" of the rotary envelope making machine, and which rollers feed the envelope blanks or the web material from a previous operating station to a subsequent station. For simplicity of illustration and understanding of the present invention, these steps of the envelope making machine are not shown, as they specifically form no part of the present invention, it being sufficient that the rollers "B" and "D" of the machine guide the envelope blanks or paper web material into and from the window forming apparatus 1.

25 The window forming apparatus 1 broadly includes a revolvable cylinder "A," around which the web material or blank is extended as it passes from the guide roller "B" to the guide roller "D," a grinding cylinder or wheel "C" that cooperates with the cylinder "A" to grind through the material of the blanks or web, pressure rollers 30 "F" and "G" for pressing the material of the blanks or web to the cylinder "A," a mechanism "E" for moving the grinding wheel to and from the cylinder "A," and a scrap collector "H" for receiving the material ground out of the blanks or web.

35 The cylinder "A" and guide rollers "B" and "D" are supported on horizontal shafts 2, 3 and 4 to carry the web or blanks 5 between the peripheral faces 6, 7 and 8 thereof, whereby the blank or web 5 is guided to and from a wrapping relation with the cylinder "A." The shafts 40 2, 3 and 4 are driven in timed relation by gearing, as indicated at 9, FIG. 3, and which in turn is operated in timed relation with the operating parts of the previous and subsequent stages of the envelope making machine, not shown. The blank or web 5 thus extends a substantial distance around the cylinder "A" to accommodate the pressure rollers "F" and "G," the grinding roller "C," and the scrap collector "H," so that the entire window-forming operations are carried out while the blank or web is carried around the cylinder "A." The cylinder 45 "A" comprises a core 10 having end disks or flanges 11 and 12. The core is adjustable longitudinally of the shaft 2 by collars 13 and 14 to position the window opening in the blank or web. The cylinder "A" also has a bar 15 extending parallel with the shaft 3 and has its ends 50 fixed thereto by collars 16 and 17, the flanges 11 and 12 being provided with notches 18 to pass the bar 15 there-through. Fixed to the core 10 and extending radially thereof is a plate or pad 19 having an arcuate outer face 20 inset below the peripheral faces 21 of the flanges 55 or disks 11 and 12 to accommodate an arcuate platen 22 thereon, so that the outer face 23 of the platen 22 registers laterally with the peripheral faces 21 of the

60 65 70

disks 11. In the illustrated instance, the platen 22 is in the form of an elongated rectangle, having the long side faces 24 and 25 thereof extending in the longitudinal direction of the cylinder "A" and the end faces 26 and 27 extending in the circumferential direction of the cylinder "A." It is to be understood that the platen 22 may be other shapes and sizes, dependent upon the shape of the opening to be formed. Surrounding the platen 22 and held in face to face contact with the side and end faces 24-25 and 26-27 thereof is a thin, flat, hardened band 28, which, for example, may be 0.1 mm. in thickness. However, it is to be understood that the material of the band 28 may be thicker, as may be required in accordance with the thickness of the envelope material or the speed with which the machine is operated. The band 28 provides a frame on the cylinder "A" and is preferably mounted with its inner edge 29 bearing upon the face 20 of the pad 19 and its outer edge 30 projects slightly beyond the face of the platen 22 and the peripheral faces 21 of the disks 11 and 12 to constitute supports for the envelope material. The supports thus provided locate the site of the perimeter of the window opening to be formed. The band 28 is clamped to the side and end faces 24-25 and 26-27 of the platen 22 by clamping strips 31 that are secured to the pad 19 by fastening devices such as screws 32. The width of the band and the depth of the side and end faces of the platen 22 are such that the edges 30 of the band project from the surface 23 of the platen, as indicated by the distance "a" designated in FIGS. 2 and 3.

The bar 15 has an arcuate face 33 registering with the peripheral faces 21 of the disks 11 and 12 of the core 10 and which is carried under the roller "B" to engage the blank or web to carry it around the cylinder "A." In order to grip the blank or web, the arcuate face 33 has a plurality of ports 34 through which a vacuum is drawn by way of channels 35 extending longitudinally of the bar 15 and which connects at one end with a radial port 36 in the collar 17 and which in turn connects with a channel 27 extending longitudinally of the shaft 3, the outer end being closed by a plug 38. The vacuum is drawn through the ports and channels through a radial port 39 in the shaft and which connects with a channel 40 in a valve disk 41 that rotates in contact with a plate 42 having a channel 43 that connects with a source of vacuum, not shown. The valve disk 41 and plate 42 have ports 44 and 45 that are adapted to register near the point where the face 33 of the bar 15 makes contact with the blank or web to carry the blank or web around the cylinder "A" to the roller "B," where the ports 44 and 45 move out of contact to break the vacuum and release the blank to the roller "D." A blank or web is thus held to the cylinder "A" and extended over the face of the platen 22 and the projecting outer edges 30 of the band 28 with the blank or web bearing directly upon the edges 30 of the band.

The grinding wheel "C" includes a cylindrical body 46 that is supported concentrically on a shaft 47 and between clamping disks 48 and 48'. The ends of the shaft 47 are suitably journaled in bearing brackets 49 and 50 that are carried upon a table 51 of the mechanism "E." The table 51 is carried on an under table 52 that is mounted on a bed frame 53. The under face of the table 52 has a transverse dovetail groove 54 engaging a transverse dovetail 55 on the bed frame, whereby the table 52 is adapted to be moved transversely to center the grinding wheel "C" in proper registry with the lateral adjustment of the platen 22. The table 52 is actuated transversely by a threaded shaft 56 which is operated by a hand wheel 57, the shaft 56 being rotatably carried by the bed frame and having threaded connection with a depending lug 58 on the under side of the table. The grinding wheel "C" is driven at high speed by means of a pulley 59 (FIG. 3) that is actuated through a belt connection with a motor or a rotary part of the envelope making machine.

5 The grinding face 60 of the grinding wheel "C" is cylindrical to make tangential contact with those portions of the material of the blank or web backed by the outer edges 30 of the band 28, whereby only the portion of the material extending across the edges of the band is removed by grinding, to thereby cut out a portion 61 of waste material corresponding in shape to the platen 22, and which, when subsequently removed, together with the material removed by grinding, leaves an opening in the blank or web to form a window opening.

10 The grinding wheel "C" is moved to and from the cylinder "A" by shifting the table 51 on the table 52. The plate 52 carries spaced apart guide shafts 62 and 63 that are carried between ears 64 on the table 52 and which pass through depending ears 65 on the table 51 (FIG. 1). The supporting table 51 is shifted by means of a shaft 66 having a threaded end 67 rotatable in a nut 68 that depends from the table 51, as shown in FIG. 1. The ends of the shaft 66 are suitably journaled in lugs 69 and 70 on the table 52, also best shown in FIG. 1. One end of the shaft 66 carries a worm gear 71 which meshes with a worm 72 on a shaft 73 which is adapted to be turned manually by a hand wheel 74 on the outer end of the shaft 73. The shaft 73 is locked in adjusted position by a jamb nut 75, as shown in FIG. 3. The worm shaft 73 is rotatably mounted on the table 52 in suitable bearings 76.

15 The pairs of rollers "F" and "G" consist of rubber or other yieldable material and are journaled in arms 77 and 78 pivotally mounted on the bearing brackets 49 and 50 of the table 51, so that the resilient peripheries 79 thereof press the blank or web and serve to secure the material to the surface 21 of the disks 11 and 12 as it passes between the cylinder "A" and the grinding wheel "C," and to hold it under tension while the window is being ground to the size determined by the edges 30 of the band 28.

20 The waste pieces ground out of the material of the blanks or web are discharged by blasts of air into the waste collector "H." This is accomplished by admitting compressed air through a port 80 in a valve plate 81 that contacts an adjusting disk 82 which engages the opposite side of the valve disk 41. The air is discharged through a port 83 in the valve plate 81 at the time the platen is moved across the open top of the scrap collector "H." The port 83 of the valve plate connects with a channel 84 that extends longitudinally of the shaft 2 and discharges through a radial port 85 into an internal annular recess 86 of the core 10. The air then passes through radial ports 87 that extend through the pad 19 and platen 22 to discharge against the face of the waste material and blow it from the face of the platen into the scrap collector "H." The ports in the valve plate and disk are so located that the air pressure will be shut off as the bar 15 of the cylinder passes the holder and to allow the face of the bar to cooperate with the feed cylinder "D" for continuing the movement of the blank or web after the opening has been formed therein.

25 Assuming that the window-forming apparatus is constructed and installed in a rotary type envelope making machine, with the grinding wheel "C" imposed in co-operation with the feed rollers "B" and "D," and assuming that the proper shaped band 28 and platen 22 have been applied to the arcuate surface 20 of the pad 19, the operation is as follows:

30 When the envelope making machine is of the web type, the web 5 from which envelopes are formed is passed under the feed roller "B" and around the cylinder "A" and over the roller "D," so that the envelope material is convexly curved around the cylinder "A." Threading of the web is most easily accomplished when the grinding wheel is in retracted position. This is effected by loosening the jamb nut 75 and rotating the hand wheel in the proper direction to turn the worm gear 71 and the screw shaft 66, so that the nut 68 is moved retractively on the

threaded end 67 of the shaft. After the web is in position and the core of the cylinder "A" has been adjusted on the shaft 2 to properly locate the band 28 in relation to the site of the window opening to be formed, the hand wheel 57 is operated to adjust the grinding wheel relatively to the lengthwise direction of the platen. This is effected by turning the hand wheel 57 in the proper direction to shift the table 51. The hand wheel 74 is then operated to turn the shaft 66 and shift the table 51 so that the grinding wheel is in a position to grind through only those portions of the material of the paper web that overlie and are supported directly upon the outer edges 30 of the band, and to bring the pairs of resiliently faced rollers "F" and "G" into position for engaging the sides of the web overlying the peripheral faces 21 of the flanges or disks 11 and 12 to smooth the material of the web which spans the space between the supported portions thereof.

When the machine is in operation, the rollers "B" and "D" and cylinder "A" all rotate in timed relation with the various stage operations (not shown) of the envelope making machine, so that the window openings are formed in the proper spaced apart location in the lengthwise direction of the web 5. During rotation of the cylinder "A," the bar 15 passes under the feed roller "B" and the vacuum is established through the ports 34 to draw the web into contact with the arcuate face 33 of the band and to grip the web so that as the cylinder "A" revolves, the web is drawn tightly over the outer edges 30 of the band 28. As the band is carried toward the grinding wheel, the periphery of the grinding wheel first contacts the material of the web extending over the advanced longitudinal edge of the band 28, grinding through the material to form a linear slitlike opening along the length thereof, and as the cylinder "A" continues its rotation, the grinding action is concentrated along the portions of the material engaging the arcuate edge faces of the end-most portions of the band to effect similar slitlike openings at right angles to the ends of the first formed slitlike opening, and as the portion of the material overlying the outer edge of the rearmost portion of the band comes into position, a corresponding linear slit is ground thereby by the grinding action of the wheel "C." The material surrounded by the slitlike openings thus formed is not affected by the grinding wheel, but provides an intact panel that is carried with the web over the collector "H." By this time the valve disk 81 has moved into position so that blasts of compressed air are discharged through the ports 87 to displace the waste material that is encompassed by the slits or narrow slots thus formed into the collector "H." When the air supply port is moved out of registry, the air blast is shut off and the web continues its travel around the roller "D."

If the apparatus has been installed in a machine adapted for feeding blanks from a stack, the blanks are fed from the stack and passed through the machine in successive order, so that they pass through the window-forming apparatus substantially in the same manner as the web just described.

It is obvious that the invention provides an apparatus for accurately and neatly forming windows by supporting the sheet material, of which the envelopes are constructed, within and along the perimeter of the opening to be formed, and that only the supported material is ground through in the grinding step to provide a very narrow slit or slot coextensive with the perimeter of the opening to leave a substantially solid panel of waste material within the enclosing limit of the slit, and that the opening is completed by displacing the panel of waste material which is encompassed by the slit. It is also obvious that all of the steps are adapted to be carried out while maintaining the envelope material convexly curved and in motion through a curved path to facilitate the grinding step.

From the foregoing, it is obvious that the grinding

wheel, in cooperation with the projecting edges of the band on the revolving cylinder "A," provides for formation of the window openings at high speed and while the blanks or web are also traveling at high speed through the machine. It is also obvious that the thinness of the band and high speed of the grinding wheel result in a smoothly continuous edge about the perimeter of the window opening and that all of the window openings are of the same size and shape, since the size and shape is controlled by the size and shape of the band.

What I claim and desire to secure by Letters Patent is:

1. An apparatus for producing openings in sheet material of which envelopes are formed, including a rotatable member, means supporting said member for rotation on a fixed axis, a frame on said rotatable member and having a relatively thin edge defining the site of the perimeter of the opening to be produced, means on said rotatable member for gripping the sheet material to carry the sheet material over said frame and across the relatively thin edge thereof, a grinding wheel having a cylindrical grinding surface, means for supporting the grinding wheel with its axis in parallel relation with the axis of the rotatable member and with the cylindrical grinding surface thereof adapted to progressively contact the portions of said sheet material backed by said thin edge, and means for operating the grinding wheel to grind through said portions of the sheet material to provide a rectangular slit in said sheet material for forming the perimeter of said opening.
2. An apparatus for producing openings in sheet material of which envelopes are formed, including a rotatable member, means supporting said member for rotation on a fixed axis, a generally rectangular frame on said rotatable member and having a relatively thin edge defining the site of the perimeter of the opening to be produced, means on said rotatable member for gripping the sheet material to carry the sheet material over said frame and across the relatively thin edge thereof, a grinding wheel having a cylindrical grinding surface, means for supporting the grinding wheel with its axis in parallel relation with the axis of the rotatable member and with the cylindrical grinding surface thereof adapted to contact the portions of said sheet material backed by said edge of the rectangular frame, means for operating the grinding wheel to grind through said portions of the sheet material to provide a rectangular slit in said sheet material for forming the perimeter of said opening and to leave a substantially solid panel of waste material, and means for discharging air under pressure through an area of the rotatable member bounded by said frame and against the panel of waste material encompassed by said rectangular slit.
3. An apparatus for producing a window opening in sheet material of which envelopes are formed, including a rotatable member, means supporting said member for rotation on a fixed axis, a platen conforming in shape to the opening to be formed and having a curved surface concentric with the axis of rotation of said member, means for securing the platen to the rotatable member, a relatively thin band surrounding the platen and having an edge projecting outwardly from the curved surface of the platen, means for clamping the band to the platen, means on said rotatable member for gripping the sheet material to carry the sheet material over said platen and across said projecting edge of the band for locating the perimeter of said window opening, a grinding wheel having a cylindrical grinding surface, means for supporting the grinding wheel with its axis in parallel relation with the axis of the rotatable member and with the cylindrical grinding surface thereof adapted to progressively contact the portions of said sheet material on said projecting edge of the band to provide a slit about the perimeter of said window opening, and means for operat-

ing the grinding wheel to grind through said portions of the sheet material.

4. An apparatus for producing a window opening in sheet material of which envelopes are formed, including a rotatable member, means supporting said member for rotation on a fixed axis, a platen conforming in shape to the opening to be formed and having a curved surface concentric with the axis of rotation of said member, means for securing the platen to the rotatable member, a relatively thin band surrounding the platen and having an edge projecting outwardly from the curved surface of the platen, means for clamping the band to the platen, means on said rotatable member for gripping the sheet material to carry the sheet material over said platen and across said projecting edge of the band for locating the perimeter of said window opening, a grinding wheel having a cylindrical grinding surface, means for supporting the grinding wheel with its axis in parallel relation with the axis of the rotatable member and with the cylindrical grinding surface thereof adapted to contact the portions of said sheet material on said projecting edge, means for operating the grinding wheel to grind through said portions of the sheet material for forming a slit about the perimeter of said window opening and leave a substantially solid panel of waste material encompassed by said slit and conforming to the shape of the platen, said platen having ports extending through the platen, and means associated with the rotatable member for discharging air through said ports for displacing the panel of waste material encompassed by said band.

5. An apparatus for producing openings in sheet material of which envelopes are formed, including a rotatable member, means supporting said member for rotation on a fixed axis, a platen conforming in shape to the opening to be formed and having a curved surface concentric with the axis of rotation of said member, means for securing the platen to the rotatable member, a relatively thin band surrounding the platen and having an edge projecting from the curved surface of the platen, means on said rotatable member for gripping the sheet material to carry the sheet material over said platen and across said projecting edge of the band, a grinding wheel having a cylindrical grinding surface, means for supporting the grinding wheel with its axis in parallel relation with the axis of the rotatable member and with the cylindrical grinding surface thereof adapted to contact the portions of said sheet material on said projecting edges, pressure wheels carried by the grinding wheel supporting means for contacting the sheet material on opposite sides of the platen, means for shifting the grinding wheel supporting means to adjust contact of the grinding wheel, means for operating the grinding wheel to grind through said portions of the sheet material, and means associated with the rotatable member for displacing the material overlying said platen.

6. In an apparatus for producing windows in envelopes, a rotatable shaft, a core member adjustable longitudinally on the shaft and having end flanges providing peripheral faces for supporting the sheet material of which the envelopes are formed, a transverse bar extending along said shaft and through said flanges and having an arcuate face registering with the peripheral faces of the flanges, a pad carried by the core intermediate of the flanges, a platen supported on the pad, a band surrounding the platen with one edge abutting

the pad and the other edge projecting radially from the face of the platen, said bar having vacuum ports extending through the arcuate face thereof for drawing a vacuum to effect gripping of the sheet material of which the envelopes are formed and to effect wrapping of the sheet material over the platen and across the projecting edges of the band, a grinding device having a grinding surface, and means for supporting the grinding device with the grinding surface thereof in grinding contact with the portions of the sheet material that are carried across said projecting edges of the band.

7. In an apparatus for producing windows in envelopes, a rotatable shaft, a core member adjustable longitudinally on the shaft and having end flanges providing peripheral faces for supporting the sheet material of which the envelopes are formed, a transverse bar extending along said shaft and through notches in said flanges and having an arcuate face registering with the peripheral faces of the flanges, a pad carried by the core intermediate of the flanges, a platen supported on the pad, a band surrounding the platen with one edge abutting the pad and the other edge projecting radially beyond the face of the platen, said bar having vacuum ports extending through the arcuate face thereof for drawing a vacuum to effect gripping of the sheet material of which the envelopes are formed and to effect wrapping of the sheet material over the platen and across the projecting edges of the band, a grinding device having a grinding surface, and means for supporting the grinding device with the grinding surface thereof in grinding contact with the portions of the sheet material that are carried across said projecting edges of the band.

8. An apparatus for producing windows in envelopes including a supporting device provided with a generally rectangular frame having a relatively narrow edge projecting from the supporting device for backing the sheet material and defining the site of the perimeter of the window in said sheet material, means for movably mounting the supporting device, a grinding device having a grinding surface movable across said relatively narrow edge of the frame, means for feeding the sheet material of which such envelopes are formed between said frame portion of the supporting device and said grinding surface of the grinding device, means on the supporting device for gripping the sheet material for movement therewith, means on opposite sides of the grinding device for pressing the sheet material against the supporting device on opposite sides of the frame for smoothing the sheet material across said frame, and means for actuating the grinding device for grinding through the portions of the material extending across the relatively narrow edge of said frame to provide a continuous slit forming the perimeter of the window.
